US0D1052343S

(12) **United States Design Patent** (10) Patent No.: **US D1,052,343 S**
(45) Date of Patent: ** Nov. 26, 2024

(54) **FLUID CONTAINER**

(71) Applicant: **HidrateSmart LLC**, Henderson, NV (US)

(72) Inventors: **Coleman Iverson**, Minneapolis, MN (US); **Alexander Hambrock**, Chicago, IL (US); **Paul Baird**, Chicago, IL (US); **Chris Sweet**, Minneapolis, MN (US); **Marcus Papadopoulos**, Minneapolis, MN (US)

(73) Assignee: **HidrateSmart LLC**, Henderson, NV (US)

(**) Term: **15 Years**

(21) Appl. No.: **29/803,112**

(22) Filed: **Aug. 10, 2021**

(51) LOC (14) Cl. **07-01**

(52) U.S. Cl.
